CLAIM

The ornamental design for a trailer hitch, as shown and described.

DESCRIPTION

FIG. 1 is a perspective view of a trailer hitch, showing my new design, the draw bar being in retracted and centered position;

FIG. 2 is an elevational view of one side thereof, the opposite side being a mirror image of the figure shown;

FIG. 3 is a top plan view thereof;

FIG. 4 is a bottom plan view thereof;

FIG. 5 is a front elevational view thereof;

FIG. 6 is a rear elevational view thereof;

FIG. 7 is a perspective view similar to that of FIG. 1 with the draw bar in extended and centered position and with the draw bar locking pin in elevated condition;

FIG. 8 is a top plan view similar to that of FIG. 3 with the extended draw bar in one extreme lateral position; and

FIG. 9 is a top plan view similar to that of FIG. 8 with the extended draw bar in the opposite extreme lateral position.
